Application October 5, 1933, Serial No. 692,322

4 Claims. (Cl. 200—48)

This invention relates to improvements in electric switches, and more particularly to sectionalizing switches adapted to be incorporated within a high voltage transmission line to facilitate the disruption of a section of such line and the invention also relates to isolating or disconnecting switches. The switch, as a rule, is mounted upon a steel tower or other support and is customarily controlled with other similar switches by a single 5 switch handle located on the tower at a remote point.

It is characteristic of such switches that they must be designed to conduct considerable current and therefore provision must be made for a quick make and break to inhibit destructive arcing forces. Furthermore, it is essential that the air gap between the parts of a switch unit, when in open position, be as great as possible to prevent the current from jumping across these 10 parts.

The primary object of my invention is to provide an improved disconnecting or sectionalizing switch of the rocking insulator type whereby to obtain a relatively large movement of the blade by making a relatively small movement of the 15 rocking insulator, and to provide a construction such that, when the switch is used as an isolating or disconnect switch, mounted vertically, the rocking insulator will not collect water.

Another object of the invention resides in the provision of means whereby the moving insulator may be swung through approximately sixty degrees for a mounting in a horizontal position, or when used as a sectionalizing switch and through 20 thirty degrees for a mounting in a vertical position or when used as an isolating or disconnecting switch.

Another object of the invention resides in the provision of an adjustable interchangeable link 25 utilized in the switch leg system or system of links, said link being capable of use in either type of switch referred to above, thus obviating the necessity of carrying extra parts on hand for use when conversion from one type of switch to another type is desired.

Switches of the type referred to are usually located in the open air and are therefore exposed to the elements such as dirt, factory dusts, sleet and ice, thereby bringing unusual operating conditions into being. When snow and ice collect on the contacts, it is difficult to open the switch. Again, the switches often remain inoperative for long periods of time and as a result, the parts have a tendency to hold together or stick. In 30 the construction of the present invention, the

initial opening movement of the switch is aided by providing a pivoted cooperating contact on the end of one of the sections comprising the linkage, thereby providing some movement in the initial opening movement to break any tendency 35 of the parts to stick, bind or freeze.

The invention will be better understood from the following description when considered in connection with the accompanying drawings.

In the drawings, Fig. 1 is a side elevation of a 10 single pole switch, that portion in dotted lines representing the closed position and the full line position representing the position taken when a small initial releasing or breaking movement has taken place;

Fig. 2 is a side elevation of the switch in open position;

Fig. 3 is a side elevation of the switch in full open position;

Fig. 4 is a vertical elevation of the counterbalance spring which is mounted on the shaft used to operate a plurality of switch units;

Fig. 5 is a vertical elevation view of the stationary contact member, parts thereof being broken away and in section in order to more 25 clearly illustrate structural details;

Fig. 6 is a view showing the adjustable interchangeable link forming a section of the switch linkage;

Fig. 7 is a section on line 7—7 of Fig. 6;

Fig. 8 is a section on line 8—8 of Fig. 6;

Fig. 9 is a section on line 9—9 of Fig. 1;

Fig. 10 is a side elevation of the switch shown as mounted in a vertical position to function as an isolating or disconnecting switch, the dotted 35 line position representing the switch in closed position.

Referring more particularly to the drawings, in which like numerals designate like parts throughout the several views, the numeral 6 represents 40 an angle iron or the like mounting base, which is part of a transmission tower. Pedestals 7 are mounted on this base by means of bolts. The bases or supports 8 and 8' of insulators 10 and 11, of the petticoat type, are secured to the pedestals, 45 in the case of base 8, by means of bolts 9 and in the case of base 8', by means of screw threads or the like. The insulators 10 and 11 are termed stationary insulators and are spaced as shown in Fig. 1. When mounted as shown in Fig. 1, the 50 switch is horizontal, on the top of the tower, and is used as a sectionalizing or "load break" switch, to break the continuity of the conductors forming the transmission system. Intermediate the insulators 10 and 11 is a rocking insulating sup- 55

port 12, mounted in alignment with the insulators 10 and 11 for movement about an axis substantially perpendicular to the plane of the insulators 10 and 11. For this purpose, the insulator 12 5 may be secured to a rock shaft 13, in any suitable manner, the shaft being so arranged as to be actuated by the mechanism shown, comprising a crank 14 and an operating rod 15 which in turn is connected to a handle (not shown) located on 10 the tower at a remote point. While Fig. 1 shows but a single pole switch or switch unit it is perfectly obvious that two or more similar units may have their rocking insulators mounted on the same rock shaft so as to be actuated simultaneously. The supporting insulators of said additional units are mounted on angle iron bases, similar to base 6, on the top of the tower, and all 15 of the bases are arranged in parallel relation.

Fixed on the outer ends of insulators 10 and 20 11 are heads or caps 16 and 17, respectively, mounting brackets 18 and 19, respectively. On the bracket 18 is mounted the stationary contact member 20, more clearly shown in Fig. 7 and to be 25 described in detail, later. To the stationary contact member are secured flexible conductors 21, and these are in contact with a clamp type terminal 22, to which the transmission line conductor is clamped. The clamp type terminal is also furnished with a bolted connector 23 secured to 30 the contact member 20. This bolted connector is adapted to receive the mounting ends of each of two fixed arcing horns 24, 24, said arcing horns rising vertically and being spaced and parallel with respect to each other.

35 The stationary contact 20 shown in detail in Fig. 5, comprises, among other features a pair of switch blade contact members 25, each blade contact member being mounted on a shaft 26 secured in the primary guide or housing 27, the contact 25 being urged toward the switch blade by means of a spring 28, surrounding said shaft and held between the contact 25 and the member 28' carried by the shaft 26, said member abutting the housing 27. An adjustable nut 29, having a half round contact face is threaded upon shaft 26, said nut being backed up by a lock nut 30. Maximum pressure upon the contact 25 is maintained by the spring 28 which constantly exerts pressure against contact 25 and member 28'. 40 When the cooperating contact element or switch blade is withdrawn, nut 29 engages housing 27 and prevents spring 28 from urging contact 25 too far to a position which would prevent the switch blade from making entry again between the contacts 25. The contact housings 27 are brought together at their bases by means of a bolted connection 31 which also serves to mount the stationary contact member, designated as a unit by the numeral 20, on the bracket 18. A 45 bolted shaft 32, also tying the housings 27 together, and passing through the contact members 25, serves as a stop for the switch blade, to prevent the latter from falling below the lower margins of the contacts 25.

50 The cooperating contact element or switch blade 40 is held in a switch blade holder 41, said holder comprising similar spaced members adapted to receive the blade 40 between them, said blade being pivoted on a shaft 42, connecting the sides of the holder together. Each of the sides of the blade holder is provided with an integral struck up portion 43, said portions mounting a cross piece 44 to which piece one end of the moving arcing horn 45 is attached, the other end of 55 said arcing horn being attached to a shaft 46

(see Fig. 9). The blade is held normally in alignment with the longitudinal axis of the blade holder by means of a contractile spring 47, one end of said spring being attached to the blade and the other end of said spring being attached to the blade holder. As will appear from Figs. 1 and 9, the parallel sides of the blade holder are pivoted on a shaft 46, passing also through the spaced trunnion members 48, 48' integral with the bracket 49 mounted on the moving insulator 12. As shown in Fig. 9 the sides of the blade holder merge into an integral member 52, or in other words, this integral member is bifurcated, the respective bifurcations being the sides of the blade holder. The trunnion members 48, 48' at their upper extremities are each provided with an inwardly offset integral part 50, constituting a stop, against which the sides of the blade holder will abut when the switch blade is moved to an open position, (see Fig. 2). Also, as shown in Fig. 9, the upper extremities of the members 48, 48' constitute securing members for each of two contractile springs 51, said springs also being secured in the struck-up portions 43 of the blade holder. The purpose of said springs will later 25 reveal itself.

The blade holder, which is pivoted as described to the rocking insulator is also pivoted at 60 to two spaced parallel members 61, designated as switch legs. The blade holder may also be considered as a link and likewise the spaced parallel members make up a section of a linkage system. Another pair of spaced parallel switch legs 62 comprising another section of a linkage system is pivoted at 63 and also pivoted to the bracket 35 19 at 64. A contractile spring 65 connects elements 61 and 62. To the bracket 19 is secured the terminal 66, to which the transmission line conductor is attached. A pair of braided shunts or conductors 67 lead from the terminal 66 to the 40 blade 40 and are secured by separable keepers 68 to the switch legs and also secured to the blade by bolts and nuts 69.

Very often, in the operation of switches of the prior art, it has been found necessary in opening 45 or closing a switch, to slam the same so that the blade will be seated properly. Gradually through use or faulty construction, considerable loose play develops in the switch parts and consequently when closing a switch, the blade may have a 50 tendency to go down between the contacts too far and a poor contact will be the result.

Now, to obviate this fault, provision is made for an adjustable link or blade adjustor, interchangeable as between various types of switches. 55 This adjustable link is shown at 80 and comprises an elongated member pivoted at 81, between the switch legs 61 and provided with a slot 82 extending from the free end of the link, lengthwise to a point substantially midway thereof. Said slot 60 has parallel edges and the edges are also provided with teeth of the shape shown in Fig. 6. Bolts 83 and 84, similar to carriage bolts are inserted in this slot and are adjustable to any point along the length of said slot by means of nuts 83' and 65 further held by said teeth. The switch legs 62 are provided with a pivot 85 which rides in said slot freely and will abut against the bolts 83 and 84 at whatever points in said slot said bolts are secured.

70 Viewing Fig 1, the full line position shows the switch blade not quite in its closed position. To bring it to its fully closed position, the rocking insulator 12 is moved to the left by means of the rod 15 and the blade gradually straightens 75

out and assumes the dotted line position. At the same time, the various sections of the linkage system have functioned and in accordance with a predetermined adjustment of the bolts 83 and 84, the links 62 carrying the sliding pivot 85, cause this pivot to move in the slot and abut the bolt 84, thus preventing any further movement of the linkage system or of the switch blade. Inaccuracies of assembly are therefore taken care of and it is unnecessary to slam the switch. As shown in Fig. 3, in which the switch is in full open position, the pivot 85 engages the bolt 83, thus preventing any further opening of the switch. Due to the fact that the pivot 81 is removable, the same link 80 may be interchangeable so as to mount the same on the switch legs 62 by means of the pivot 81, as shown in Fig. 10, and the slideable pivot 85 will be carried by the switch legs 61. This arrangement of the adjustable link 80 is desired where the switch is mounted vertically to be used as an isolating switch, in connection with oil circuit breakers or the like. The principal point is that the same link may be used interchangeably regardless of whether the switch is to be mounted horizontally, or vertically and therefore it is unnecessary to carry in stock, various sizes or types of links for varying types or mountings of switches.

A forward or backward positive adjustment, by means of the link, can be made to compensate for any irregularities or discrepancies in assembly so that the switch blade will make perfect alignment with the stationary contact. In other words, the center line of the blade can be made to coincide with the center line of the stationary contact. In substantially all other types of switches this operating fault has been a source of trouble. It may be overcome by slamming the switch but this is not desirable. The use of the adjustable link results in such positive operation that even operating shaft torque may be compensated for and when several blades are being actuated simultaneously, said blades will seat without slamming the switches.

As stated, the invention also seeks to provide an arrangement of parts whereby during the initial breaking period, a quick break will be obtained and the moving parts will be vertically accelerated at a rapid rate, to dissipate the power arc. This is not a characteristic of structures in the prior art, since the blade usually moves with the moving insulator and in a few instances, it moves but negligibly greater than the moving insulator.

As mentioned previously, the switch legs 61 and 62 are mechanically connected to the link 80. As the insulator 12 moves from closed to open position, the link 80 tends to lock these switch legs in such a position as to throw the switch blade holder 41 through an angle of approximately 60 degrees, at a predetermined point and actuated by the contractile spring 65, thereby obtaining the "quick-break" so essential at the point when the moving arcing horn 45 leaves the fixed horns 24. The moving horn moves through an approximate angle of 60 degrees while the moving insulator moves through an approximate angle of 6 degrees, and therefore there is a relative movement of the moving horn approximately ten times as fast as the movement of the moving insulator.

Referring to Fig. 1, the dotted line position of the blade and the rocking insulator depicts the switch in closed position. To open the switch

and initiate the break of the current, the insulator 12 is moved from the dotted line position, normally about six degrees, by means of the rod 15 and link 14. This movement causes the blade to take the full line position, which is somewhat "cocked", placing the spring 47 under tension but still keeping the blade in substantial contact with the stationary contacts. Spring 47 has the tendency to continually bring blade 40 back into alignment with blade holder 41 and destroy the "cocked" position. Such "cocked" position will be destroyed as soon as the blade 40 has been pried free of the contacts 25. In addition, springs 51, on the blade holder, have been tensioned to a great extent, thereby storing up enough energy which when released, and when supplemented by the action of link 80 and pivotal connection 60, causes the blade to be quickly broken away from the contacts and immediately the blade assumes the position shown in Fig. 2; that is, the blade 20 has been vertically accelerated to a position where the power arc is dissipated and the blade has moved through an angle of approximately sixty degrees as compared to an approximate six degrees movement of the rocking insulator. Therefore it will be seen that the blade moves approximately ten times as fast as the element responsible for its movement; that is, the rocking insulator. Having dissipated the power arc, the switch can be moved to the full open position, shown in Fig. 3, and for this movement, the rocking insulator will describe an angle of approximately sixty degrees. In the position shown in Fig. 3, the switch parts have been brought to such a position that it is practically impossible to have the current flash over from the blade to the stationary contact. The spring 65 contributes slightly to the quick breaking action referred to but the system will function as well without it.

Referring now to Fig. 10, it will be seen that the same switch may be made to function in double duty capacity, that is, by making a few changes, about to be described, the switch will function as an isolating or disconnecting switch by mounting the same in a vertical position to the side of the transmission tower. However, as those skilled in the art are well aware, a pin type insulator cannot be mounted in a position greater than ninety degrees to the vertical (considering the first quadrant) or inclined, at an angle to the horizontal (considering the second quadrant), for in exceeding these limitations, the electrical efficiency of the insulator is reduced, due to the fact that water will collect in the petticoats and cause the insulator to rupture during a wet flashover. Therefore, the stationary insulators, 10 and 11, are mounted at a ninety degree angle to the vertical. The dotted line position shows the switch in closed position and as in the case of Fig. 2, the blade during its power arc dissipating movement will still describe an angle of sixty degrees but in moving the rocking insulator to the full open position, as shown in Fig. 10, an angle of but thirty degrees is described; that is, the angle between the center line of the rocking insulator in dotted position and between the center line of the rocking insulator in full open position is but thirty degrees. The interchangeable adjustable link 80, as used in Fig. 1, is pivoted at 81 to the switch legs 62 and the sliding pivot 85, riding in slot 82, is carried by switch legs 61, so that the link takes the position as shown in Fig. 10, somewhat in the nature of a knee brace. The link performs the

same function in the switch shown in Fig. 10, as it does in the switch shown in Fig. 1. The operating crank 14 and the rod 15 are changed, as shown, but all of the changes referred to are 5 practically instantaneous field changes, involving no changes in the size or shape of the parts employed. In the switch shown in Fig. 10, it is optional whether the stationary and quick-break arcing horns are to be installed, since as stated, 10 the switch is serving merely as a disconnecting switch and often arcing horns are unnecessary.

Figure 4 shows what is termed a counterbalance spring. When a plurality of the switch units are controlled by a single operating rod 15, due 15 to the fact that the mechanism is of considerable weight, jarring of the parts is apt to occur. The arrangement shown, eases or absorbs the shocks incidental to the coming to rest of the movable parts. A spring 100, is coiled about the 20 common operating shaft 13 and is anchored at one portion to the angle iron 6 by anchoring means 101. The other end of the spring is anchored to the shaft by clamping means 102, consisting of two halves having interior faces 25 forming to the shape of the shaft and held together by means of bolts. As the switch unit is closed, the tension of the spring increases, thereby affording some means to absorb most of the jarring incident to closing. A plurality of such 30 springs can be mounted in the same shaft, one spring individual to each switch unit, if so desired.

I claim:

1. In an electric switch of the type comprising 35 two stationary insulating supports, and a rocking insulating support mounted intermediate the stationary supports, the combination of a plurality of movable sections pivotally connected to form a linkage, one of the sections being pivotally connected to one of said stationary supports, a second section being pivotally connected to said rocking support, a third section being pivotally connected to each of said first and second sections, and a fourth section pivoted 40 on said third section and provided with an adjustable slot, said first section also being provided with a pivot for slidable engagement with said slot, said sections and said insulating supports being substantially coplanar.
2. In an electric switch of the type comprising 45 two stationary insulating supports, and a rocking insulating support mounted intermediate the

stationary supports, the combination of a plurality of movable sections pivotally connected to form a linkage, one of the sections being pivotally connected to one of said stationary supports, a second section being pivotally connected to said rocking support, a third section being pivotally connected to each of said first and second sections, and a fourth section pivoted on said third section and provided with a slot having a plurality of adjustable stops therein for adjusting 10 the length thereof, said first section also being provided with a pivot for slidable engagement with said slot, said sections and said insulating supports being substantially coplanar. 5

3. In an electric switch of the type comprising 15 two stationary insulating supports, and a rocking insulating support mounted intermediate the stationary supports, the combination of a plurality of movable sections pivotally connected to form a linkage, one of the sections being pivotally connected to one of said stationary supports, a second section being pivotally connected to said rocking support, a third section being pivotally connected to each of said first and second sections, and a fourth section pivoted on 20 said first section at a point lying between the pivotal points of connection of said first section with said stationary support and said third section respectively, and provided with an adjustable slot, said third section also being provided with a pivot for slidable engagement with said slot, said sections and said insulating supports being 25 substantially coplanar.

4. For use in an electric switch comprising 30 two stationary insulating supports, a rocking insulating support mounted intermediate the stationary supports, and a plurality of movable members pivotally connected to form a linkage and interconnecting the movable support and one of said stationary supports, one of the members of said linkage consisting of a link of elongated form provided with a fixed pivot hole at one extremity thereof and an elongated slot having parallel marginal edges extending lengthwise of said link from the other extremity thereof to substantially the midpoint of said link, said pivot hole and said slot being coplanar, the parallel edges being provided with teeth to engage a plurality of stops adjustably slidable in said slot whereby the effective length of said slot may 40 be varied. 45

ROBERT A. SANDT.
